JULIAN A. CAMPBELL, OF LONG BEACH, CALIFORNIA

PRESSURE-CONTROL APPARATUS

Application filed April 19, 1927. Serial No. 184,809.

This invention has to do with pressure control apparatus of the general type adaptable for use, as a typical example, for controlling the gas or vapor pressure in oil tanks.

5 Although there are several different objects of the present improvements, most of them will be best understood from the following detailed description. I may say preliminarily, however, that the primary object 10 of the present invention is to provide a pressure control apparatus which is capable of great sensitivity of operation, and in which the sensitivity is wholly and completely adjustable.

15 I have found in my experience that it is not only desirable to have a pressure control that is capable of extreme sensitivity, but also one in which sensitivity may be easily and readily regulated to suit varying conditions.

20 Without going into details, I may mention the fact that the amount of vapor or gas which has to be handled by such a pressure control apparatus varies from season to season and also varies under other changing conditions.

25 For instance, the variation of temperatures during summer causes oil vaporization at a rate much higher than the temperature variation in winter; and calls for an adjustment of sensitivity that will permit the apparatus 30 readily to handle a large quantity of vapor in a comparatively short time. And also, as an instance, when an oil tank is being filled or emptied rapidly, it is desirable that the sensitivity of the device may be temporarily adjusted to enable it effectively to take care of the large volume of vapor or gas which must necessarily be taken out or put into the tank to maintain an equable pressure. Furthermore, some tanks are not capable of withstanding the pressure variations that other tanks may safely stand, and so for weak tanks 35 it is especially desirable that the apparatus be adjustable to great sensitivity.

40 One of the major objects of my present invention is, by having a full adjustment of sensitivity, with a capability of extreme sensitiveness, to provide an apparatus capable of universal use.

How my present invention accomplishes its 45 purposes, and various other advantages resid-

ing in the invention, will be best understood from the following detailed description, reference for that purpose being had to the accompanying drawings, in which:

Fig. 1 is a side elevation of my improved 55 apparatus; and

Fig. 2 is a plan of the same.

I illustrate the apparatus as being mounted directly upon the top 10 of the tank, although of course it might be mounted in any other location and suitably connected with the tank. Mounting the apparatus on top the tank facilitates greatly the making of connections and puts the apparatus close to the tank so that there is no substantial delay in 60 its action and there is no liability of its being actuated by surges in pipe lines.

The gasometer illustrated at G is typical of any device which will expand and contract by virtue of variation in applied pressure. I select a gasometer for this purpose because of its comparatively great sensitivity and its freedom from friction. The gasometer will need no specific description, as devices of this general type are well 70 known; it is necessary here only to say that the movable upper member 11 of the gasometer is pivotally connected by link 12 with one end of a balance lever L which is centrally pivoted at 12a on a suitable support 13. Support 13 may be mounted on a flanged plate 14, which conveniently rests upon the bodies of the two valves 15 and 16, valve 15 being the pressure outlet valve and valve 16 the pressure inlet valve. Both these 75 valves are preferably of the balanced pressure type so that they move freely and are not affected in their movements by the pressures which they are controlling. A gas and vapor outlet pipe will ordinarily connect with valve 15 and a gas pressure inlet pipe will connect with valve 16, gas being constantly kept present at inlet valve 16 under a suitable pressure, usually a pressure substan-

55 tially higher than that desired to be maintained in the tank, and therefore valve 16 may be comparatively small. Valve 16 has a communicating pipe 18 which connects with the standpipe 19 that communicates with valve 15, and also communicates with the in-

terior of the tank, standpipe 19 serving conveniently as the supporting member for the valves and their actuating apparatus. The lower member or tank 20 of the gasometer 5 may conveniently be mounted upon angle iron members 21 which are secured to standpipe 19, the gasometer end of the apparatus being supported by a standpipe 22 which also communicates with the interior of the tank and, 10 at its upper end, with the interior of the gasometer. Angle iron members 21 serve to fix the gasometer in proper position with relation to the valve parts of the apparatus.

At the end of the balance lever L opposite 15 the gasometer a suitable weight W may be hung, this weight being conveniently in the form of a container into which a measured or ascertained weight of any suitable substance may be placed, preferably a substance 20 that does not vary in weight by exposure to atmosphere or to the weather. The amount of weight at W may thus be easily and conveniently varied to suit circumstances. The leverage system made up of the gasometer head 11, 25 lever L and weight W, may of course be adjusted to be in normal equilibrium position (in this case a substantially horizontal position of lever L) either when the pressure under the gasometer head is equal to atmospheric 30 pressure, or more or less than atmospheric pressure. For instance, if the lever arms are 35 equal and the weight at W is equal to the weight of the gasometer head, then the lever system is in equilibrium when the pressure under the gasometer head equals the atmospheric 40 pressure at that instant. Suitable variation of weight at W will make the system come to its normal position when the pressure under the gasometer head is either 45 greater or less than the atmospheric pressure; and thus, as will be seen, the apparatus can be generally adjusted to keep any desired pressure, relative to atmosphere, in the tank. The pressure in the tank is at all times maintained in a certain relation to the instant atmospheric pressure, as will be readily understood from the consideration of the nature of action of the gasometer.

In the present improved apparatus the 50 entire weight of the lever system that includes the gasometer head and weight W is supported by the support 13 and is not at any time imposed upon the valves themselves. My present system enables me to 55 impose upon the valves themselves, to close them, suitable forces determined solely with reference to the forces necessary to close the valves; not being determined or affected in the least by the weight of the gasometer head and of weight W. Each valve has a 60 stem 25 or 26 and the upper end of each stem is connected with a valve lever 27 or 28 at a point intermediate the ends of the valve lever. One end of each valve lever is 65 pivoted at 29 to the upper end of a link 30

whose lower end is pivoted at 31 to a flange of the plate 14. Each valve lever is provided with a series of holes 29a and likewise the plate 14 is provided with a series of holes 31a, so that the links 30 may be shifted in position to shift the pivot points 29 of the two valve levers toward or from the two valve stems, such adjustment being one means of adjustably varying the sensitivity of the apparatus. And it will be noted that these adjustments with relation to each valve lever may be made independently, so that the sensitivity of either valve actuation may be adjusted independently of the sensitivity of the other. In Fig. 1 for instance I show the effective pivot point 29 of outlet valve lever 27 arranged closer to the valve stem than is the case for valve lever 28 of the inlet valve. Each of these levers is provided with a suitable weight 32 sufficient to move the levers down and close the valves, the levers being raised by stirrups 33 which depend from balance lever L, these stirrups being adjustable along balance lever L to different positions. The stirrups only lift the valve levers, they cannot push the valve levers down. With the pivot point of a valve lever directly under pivot point 12a of the balance lever (as is shown to be the case for valve lever 28 in Fig. 1) it will readily be seen that the position of stirrup 33 has nothing to do with variation of the sensitivity of actuation of the inlet valve 16. However, if the pivot point of the valve lever is effectually shifted toward the valve stem, as is illustrated to be the case with valve lever 27, then the relative position of stirrup 33 is a factor in the variation and regulation of valve actuation sensitivity. It will be remarked, of course, that the amount of weight at 32, and the position of these weights on the valve levers, are also factors in the valve actuation sensitivity, and may be used as such; but in practice I prefer to use fixed weights at 32, determining those weights and their positions as being substantially sufficient always to close the respective valves, and then to obtain sensitivity adjustment by the other means here described. It is specifically one of the advantages of the present apparatus that no excessive weight need ever be applied to a valve or valve stem, thereby avoiding any liability of valve deformation and also avoiding liability of a valve sticking due to being closed under too great a force.

To illustrate the possibilities of sensitivity variation I shall refer first to the outlet valve arrangement as shown. With the stirrup 33 in the position illustrated it will be seen that balance lever L, on moving upwardly at its left hand end, as it does when the pressure in the gasometer rises, may be said to be under a leverage "disadvantage" of about 1 to 2

with relation to lever 27, the point of connection of the stirrup to lever L being about twice as far from pivot point 12a as is the point of connection of that stirrup with lever 27 from its pivotal point 29. Moving that stirrup 33 to the right will further increase the leverage disadvantage of lever L, or in other words will increase the advantage of lever 27 over lever L; while moving the stirrup 33 to the left will correspondingly decrease the advantage which lever 27 has over lever L. Thus as the stirrup 33 is moved toward the left the sensitivity of opening actuation of valve 15 is increased; that is, it requires a smaller increase in gasometer pressure to open valve 15. The limit of sensitivity would be reached in this arrangement when the stirrup is in its position furthest to the left; and if lever 27 were made long enough, as it might readily be, and stirrup 33 placed directly over the gasometer, the relative advantage of lever 27 over balance lever L will be seen to approach unity, and in that case the valve 15 would be lifted when the pressure increase under the gasometer head became a little greater than the weight 32.

If it be desired in adjustments to give neither of the levers an advantage over the other, then the pivot point of the valve lever may be arranged as is shown for the inlet valve lever 28 of Fig. 1, directly under the pivot point 12 of lever L. With that arrangement the sensitivity of opening movement of the valve is increased, because in no position of stirrup 33 does lever 28 have any advantage over lever L, with the result that (applying the observation now to lever 28 and the pressure inlet valve) the pressure inlet valve will be opened just as soon as the decrease of total pressure under the gasometer head becomes equal to a little more than the weight at 32. In speaking of increases or decreases of pressure, I mean increases and decreases with relation to the normal pressure for which weight W is set.

Thus the sensitivity of the valve actuation may be adjustably varied by two adjustments, in addition to the adjustment of weights 32. In the first place the sensitivity may be adjusted by varying the position of the stirrup 33, provided the links 30 are not directly under pivot point 12; and secondly may be adjusted by adjusting the links and the pivot points 29 toward or away from a position directly under pivot point 12. Generally speaking an adjustment of pivot points 29 toward the central position under pivot 12, the position of the stirrups being fixed, will increase the sensitivity of valve actuation, and an opposite adjustment of the pivot point 29 will decrease the sensitivity of valve actuation. And as I have before explained, an adjustment of the stirrups away from the central pivot point 12 will, if the corresponding

pivot point 29 is not directly under pivot point 12, also increase the sensitivity of valve actuation; while an opposite adjustment of the stirrups will decrease that sensitivity. Within the inherent physical limits of the apparatus the sensitivity of both valves may be adjusted as desired. Of course the greatest sensitivity of valve actuation is limited by certain fixed relations in any given apparatus. That greatest sensitivity is fundamentally determined by the size (pressure area) of the gasometer and by the weight necessary to close the valves. But I find that, without having to provide an excessively large gasometer, and still using a weight that will invariably close the valves, the maximum sensitivity of the apparatus is sufficient for all requirements. The structure and design of the apparatus are such that the gasometer may be made comparatively large and that a comparatively heavy weight may be used at W, without putting any of that dead weight upon the valves themselves. And another point which I may mention is this: that if in any case the weights at 32 should not be sufficient to move a valve closed, for instance if the valve becomes stuck, the lever L, coming down on the weight, will knock the weight and its valve lever down.

From a maximum sensitivity it will readily be seen that adjustments may be made through a range up to very coarse sensitivity, so that, if it is desired, the range of tank pressure between the pressure that opens the outlet valve and that that opens the inlet valve may be adjusted to be comparatively large. Furthermore, it will be noted that the sensitivity of either valve actuation may be adjusted in complete independence of the adjustment of the other, and furthermore that the adjustment of the main leverage system to determine the normal pressure held in the tank, is also completely independent of the sensitivity adjustments. Thus the main leverage system may be adjusted, by adjusting the weight at W, to fix any desired normal pressure which will be maintained in the tank. Suppose for instance that pressure to be two ounces per square inch above atmosphere. The weight at W in that instance will be somewhat less than it would be if atmospheric pressure were selected as the pressure to be maintained in the tank. When the tank pressure reaches two ounces per square inch above atmospheric pressure, the main leverage system will then be in equilibrium with both valves closed, the parts being in the relative positions shown in Fig. 1. Now suppose that it is desired to make the valve control extremely sensitive as to keeping the pressure up to the selected pressure of two ounces per square inch, but that it is not desired to let vapor pressure off from the tank until the vapor pressure reaches a point considerably above two ounces, in order to save vapor.

Thus for instance let us suppose that it is desired to be certain that the tank pressure will never under any circumstances fall below one ounce per square inch (to avoid any possibility of a vacuum ever developing in a tank), but that vapors will not be taken off from the tank until the pressure reaches 5 ounces per square inch. Without going into detail as to adjustments it will be readily understood from what I have said that the sensitivity of the pressure inlet valve actuation may be adjusted so that, upon a decrease of one ounce per square inch in pressure in the gasometer, the inlet valve will be lifted, feeding pressure into the tank. And likewise it will be readily understood how the leverage system for the outlet valve may be adjusted so that the outlet valve will not be lifted and opened until the tank pressure has increased by three ounces per square inch.

If for any reason it is desired either temporarily or permanently to change adjustments, such changes are very easily and quickly made. For instance if it is desired temporarily to increase the sensitivity of the outlet valve to take care of large quantities of vapor while the tank is being filled, such adjustment can be made quickly, and the adjustment as quickly changed back to normal after the filling operation is completed. Likewise sensitivity of the inlet valve may be temporarily adjusted to a very fine point so that the tank pressure may be kept up during a period when the tank is being quickly emptied. Other instances under which a temporary or more or less permanent change in adjustment may be desirable are well known to those skilled in the art and need not be detailed here by me.

I claim:

1. A pressure control apparatus, embodying an element movable by virtue of variations in applied pressure, a pressure relief valve, a pressure inlet valve, a pivoted lever actuated by said element, adjustable weight means connected to the lever and adjustably balancing it against said element, a valve actuating lever connected with each valve, said valve levers extending substantially parallel with said pivoted lever and arranged on opposite sides of its pivot point, means tending with constant force to move said levers to close the valves, and connections between the element actuated lever and the valve levers, adjustable along their length, and adapted to move the valve levers to open the valves.

2. A pressure control apparatus, embodying an element movable by virtue of variations in applied pressure, a pressure relief valve, a pivoted lever actuated by said element, adjustable weight means connected to the lever and adjustably balancing it against said element, a valve actuating lever connected with each valve, said valve levers ex-

tending substantially parallel with said pivoted lever and arranged on opposite sides of its pivot point, each valve lever having a fulcrum adjustable along its length, means tending with constant force to move said levers to close the valves, and connections between the element actuated lever and the valve levers, adjustable along their length, and adapted to move the valve levers to open the valves.

3. A pressure control apparatus, embodying an element movable by virtue of variations in applied pressure, a pressure relief valve, a pressure inlet valve, a pivoted lever actuated by said element, weight means connected to the lever and balancing it against said element to balance it normally in substantially horizontal position, a lever connected with each valve and having a fulcrum adjustable along its length to and from a position in vertical alignment with the pivot point of said pivoted lever, a weight on each of said valve levers tending to depress the levers and close the connected valves, and a connection between the element actuated lever and each of the valve levers adapted to raise the valve levers and open the valves.

4. A pressure control apparatus, embodying an element movable by virtue of variations in applied pressure, a pressure relief valve, a pressure inlet valve, a pivoted lever actuated by said element, adjustable means connected to the lever for adjustably balancing it against said element, a fulcrumed lever connected with each valve, a weight on each valve lever tending to depress the levers and to close the connected valves, and connections between the element actuated lever and each valve lever adapted to raise the valve levers and open the valves, said connections being adjustable in position along the lengths of the levers to vary the effective lever arms.

5. A pressure control apparatus, embodying an element movable by virtue of variations in applied pressure, a pressure relief valve, a pressure inlet valve, a pivoted lever actuated by said element, means connected to the lever for balancing it against said element to balance it normally in substantially horizontal position, a pair of substantially horizontal valve levers below the element actuated lever, each connected to one valve and weighted to move the valves down, and means adjustable along the length of the element actuated lever depending therefrom and adapted to engage the valve levers to raise them and their connected valves.

6. A pressure control apparatus, embodying an element movable by virtue of variations in applied pressure, a pressure relief valve, a pressure inlet valve, a pivoted lever actuated by said element, adjustable weight means connected to the lever and adjustably balancing it against said element to balance it normally in substantially horizontal position, a pair

of substantially horizontal valve levers below the element actuated lever, each connected to one valve and weighted to move the valves down, each lever having a fulcrum adjustable in position to and from its valve connection and stirrups adjustable along the length of the element actuated lever depending therefrom and extending under the valve levers to raise them and their connected valves.

5 ¹⁰ In witness that I claim the foregoing I have hereunto subscribed my name this 29th day of March, 1927.
